PIPE WRENCH

James L. Brickley, Darby, Mont., assignor of one-half to Sidney Arr Wheeler, Hamilton, Mont.

Application June 15, 1942, Serial No. 447,115

2 Claims. (Cl. 81—106)

This invention relates to pipe wrenches of the quick acting type, the primary object of the invention being to provide a pipe wrench embodying a stationary inner jaw and an adjustable outer jaw, means being provided whereby the outer jaw may be readily and easily adjusted with respect to the inner jaw, the operating means being controlled by the thumb of the hand in which the wrench is held, leaving the operator's other hand free for holding the pipe or work, during the operation of the wrench.

Another object of the invention is to provide means which will insure against the slipping of the movable jaw under excessive strain, after the proper adjustment of the wrench has been made.

Still another object of the invention is to provide anti-friction means between the shanks of the jaws of the wrench, which will permit of free sliding movement of the outer jaw under slight pressure in making an adjustment of the outer jaw, and one which is sufficiently strong to normally hold the jaws open for positioning over a nut or bolt.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing

Figure 1 is a side elevational view of a wrench constructed in accordance with the invention, a portion thereof being broken away to illustrate the construction of the anti-friction means.

Figure 2 is a plan view of the wrench.

Figure 3 is a sectional view taken on line 3—3 of Figure 1.

Figure 4 is a sectional view taken on line 4—4 of Figure 1.

Referring to the drawing in detail, the reference character 5 designates the handle of the wrench and the reference character 6 designates the stationary jaw, which is formed at the outer end of the handle 5.

Secured to the jaw 6, is a yoke 7 which extends beyond one edge of the jaw as clearly shown by Figure 1 of the drawing. This yoke 7 provides a support for the movable jaw shank 8, the movable jaw being indicated by the reference character 9. The inner surface of the yoke which contacts with the outer edge of the shank

8, is slightly curved, as clearly shown by Figure 1, so that the shank 8 will have a free rocking motion, to facilitate the positioning of the wrench over a nut or bolt to be operated by the wrench. 5 Bores 10 and 11 are formed in the edge of the jaw 6, the opening 10 accommodating the pin 12 that extends downwardly from the plate 13 that rubs the inner edge of the shank 8 of the movable jaw 9. A pin indicated at 14 extends from the plate 13 and passes into the bore 11, the pin 14 providing a support for one end of the coiled spring 15, which is shown as housed within the opening 11. Thus it will be seen that the spring 15 normally acts to urge the plate 13 outwardly against the shank 8, to the end that the movable jaw is held in a position to permit the wrench to be readily positioned over a nut or bolt.

Links 16 are connected with the inner end 20 of the shank 8, and have pivotal connection with the block 17 which is slidably mounted on one edge of the handle 5. The block 17 cooperates with the block 18 in securing the outer movable jaw in its positions of adjustment. The block 18 is formed with teeth on its inner surface, the teeth being designed to bite into the edge of the handle 5 to hold the block against movement, in one direction. The blocks 17 and 18 are held in spaced relation with 25 respect to each other, by means of the coiled spring 19 that has its ends fitted in bores formed in the adjacent ends of the blocks 17 and 18.

The reference character 20 designates a block 30 which moves along one edge of the handle 5, as clearly shown by Figure 1 of the drawing. The block 20 is arranged directly under the blocks 17 and 18, and is formed with recesses 21 in which the links 22 are held, the links being of an elongated character, so that they will fit within the recesses 22, formed in the blocks 17 and 18. Finger pieces 23 are formed at the upper ends of the links 22, and provide means to be gripped by the operator when it becomes necessary to exert pressure on the blocks 17 and 18 to move them in 35 making an adjustment of the movable jaw. Under ordinary conditions, the wrench when held in the hand of the operator, may be operated by the thumb of the hand holding the wrench, it being contemplated to thrust the block 18 forwardly, releasing the frictional contact between the blocks 17 and 18 and handle 5, so that further pressure by the thumb of the hand will cause the outer movable jaw to slide longitudinally of the handle 5, adjusting the outer movable jaw to its work. It is obvious that after the wrench has

been positioned, and a pull is directed to the outer movable jaw, caused by exerting pressure on the handle of the wrench, the blocks 17 and 18 will be forced into close engagement with the handle, holding the outer movable jaw against movement to break the adjustment between the jaws.

From the foregoing it will be seen that due to the construction shown and described, I have provided an exceptionally quick acting pipe wrench, and one in which the movable jaw thereof will be held in its positions of adjustment, when severe strain is placed on the handle of the wrench while in use. It will further be seen that although the movable jaw is securely held in its positions of adjustment, the adjustable jaw may be readily moved by the operator, when the pressure on the handle has been relieved.

What is claimed is:

1. A quick acting pipe wrench, comprising a handle, a stationary jaw at one end of the handle, a movable jaw adapted to cooperate with the stationary jaw in gripping an article, a slide block operating over one edge of the handle, a pair of slide blocks adapted to slide over the opposite edge of the handle, said blocks being in contact with the handle throughout the lengths of the blocks, links adapted to connect the movable jaw to one of the blocks of the pair of blocks, links connecting the blocks at opposite edges of said

handle, a coiled spring disposed between the pair of blocks and adapted to normally urge the pair of blocks and links engaging the blocks, away from each other, whereby a binding action is set up between the blocks and handle, holding the movable jaw in its positions of adjustment, and means for restricting movement of the movable jaw.

2. A quick acting pipe wrench comprising a handle, a stationary jaw at one end of the handle, a movable jaw adapted to cooperate with the stationary jaw in gripping an article, a movable block having recesses, positioned against one edge of the handle, a pair of links fitted in the recesses and adapted to move longitudinally of the handle, a pair of blocks movable over the opposite edge of the handle, said blocks having recesses in which said links are held, a coiled spring disposed between the blocks of the pair of blocks and adapted to separate, said blocks and links, setting up a binding action between the blocks and handle, links pivotally connecting the movable jaw to one of said blocks whereby movement of said blocks is transmitted to the movable jaw, and said blocks adapted to set up a binding action between the stationary jaw and movable jaw, holding said movable jaw in its positions of adjustment.

JAMES L. BRICKLEY.
